ART OF MANUFACTURING CURVED PRINTING PLATES

Filed Sept. 11, 1925

2 Sheets-Sheet 2

UNITED STATES PATENT OFFICE.

HARRY G. HOFF, OF CHICAGO, ILLINOIS, ASSIGNOR TO CHICAGO ELECTROTYPE AND STEREOYPE COMPANY, OF CHICAGO, ILLINOIS, A CORPORATION OF ILLINOIS.

ART OF MANUFACTURING CURVED PRINTING PLATES.

Application filed September 11, 1925. Serial No. 55,730.

This invention relates to improvements in the art of manufacturing curved printing plates, and more especially to the manufacture of such curved printing plates as used 5 on rotary presses, as, for example, electroplates comprising a sheet of metal, usually copper or nickel, and presenting the printing face, and having a relatively thick backing of metal, as, for example, what is known 10 as electrotype backing metal.

In the manufacture of such curved plates, the plate is first produced in flat form with the printing face formed thereon. Thereafter, the plate is bent to the desired curvature. My invention relates more particularly 15 to the method of and apparatus for so bending these plates.

In the bending of such plates, it is desirable to eliminate as far as possible stretching or other distortion of the printing face on the convex, or outer, surface of the plate. Such stretching causes a non-uniform distortion of the printing portions of the face with the result that accuracy in printing 25 from the plate is impaired. This inaccuracy is always more or less objectionable and particularly so when the plate is adapted for multi-color printing. In such case it is necessary that the contours of the printing portions of the successive plates used bear substantially accurate predetermined positions 30 relative to each other in order that the accurate superposing of the inks of different colors, over the desired areas may be effected. Heretofore, the bending of such plates has been accomplished by heating the electrotype backing metal to soften it, in order to lessen such stretching or distortion of the printing face during the bending operation. 35 Such heating of the backing metal, however, takes some time and requires more or less complicated apparatus.

In the bending of such printing plates while cold in accordance with the methods 45 heretofore employed, such as, for example, by the use of rollers, the sheet bearing the printing surface is caused to stretch, in the bending operation, to such an extent as to relatively greatly distort the printing portions of the plate due to the combined thickness of the plate and backing, it being understood that the sheet, and consequently the printing portions thereof, distort non-uniformly due to the irregular and non-uniform 50 contours of the printing portions, all sheets

having printing portions of different contours distorting differently.

The primary object of my invention is to bend such printing plates to the desired curvature while cold, and without substantially stretching or distorting the printing face thereof. 60

In that form of device embodying the features of my invention shown in the accompanying drawings:—

Figure 1 is a view in side elevation of a bending machine showing a part broken away, Figure 2 is a similar view in top plan, Figure 3 is a view in end elevation, Figure 4 is a vertical sectional view showing the 70 machine in operation, Figure 5 is a view taken as indicated by the line 5 on Fig. 2, and Figure 6 is an enlarged view of one end of the knife forming a part of the machine. 75

As shown in the drawings, 10 indicates a suitable base or support carrying the concavely curved bed or trough 11. 12, 12 indicate strengthening ribs for the bed 11. It will be seen that the bed or trough 11, because of its curvature, is substantially in the 80 shape of the lower half of a hollow cylinder.

At each end the bed 11 is provided with three radial arms 13 carrying a bearing 14 in which is rotatably mounted a shaft 15 axially arranged with respect to the cylindrically curved bed 11. The shaft 15 is provided at one end with a pinion wheel 16 adapted to be operated by the worm 17 which is in turn adapted to be driven by the belt-wheel 18 actuated from any suitable 90 source of power.

Rotatably mounted thereon, at each end, the shaft 15 carries a collar 19. Each of the collars 19 is provided with an upwardly projecting arm 20 and these two arms are connected by the operating bar 21. Each of the collars 19 also carries a downwardly projecting shorter arm 22 the same being connected by the presser bar 23. The presser bar 23 extends substantially the length of 100 the bed 11 and lies very close thereto. Movement of the operating bar 21 causes the presser bar to describe an arc close to and adjacent the upper surface of the bed 11. 95

24 indicates a stop bar mounted on one edge of the trough or bed 11 having one edge 24^a projecting inwardly a short distance beyond the curved surface of such bed or trough.

The shaft 15 carries a knife support 25 110

suitably braced by means of the strengthening ribs 26, 26 lying back of said knife support and integrally joined to the shaft 15. Mounted on the knife support 25 is a knife 27 by means of the set screws 28 extending through suitable slots 29 in the knife 27 to permit adjustment of said knife on said knife support. The knife 27 is also provided with a plurality of stop screws 30 on its upper edge adapted to be screwed out until their heads engage the shaft 15 and thus furnish additional security to prevent undesired sliding movement of the knife on the knife support toward the shaft. 10

15 The knife support 25 carries at each end a roller supporting member 31. Each of the members 31 carries two bearing blocks 32, each carrying rotatably mounted therein one end of a roller 33. One roller 33 lies 20 on each side of the knife 27. Each of the roller bearing blocks 32 is adapted for sliding movement in the member 31 substantially in a radial direction with respect to the axis of the shaft 15. This is accomplished 25 by providing the guides or slides 34 in which the blocks 32 are mounted. Each block 32 carries a pin or bolt 35 projecting beyond the slide 34 and provided with a head 36 to hold the block 32 in the slide. 30 37 indicates a spiral spring arranged within the slide 34 around the pin 35 tending to press the block 32 outwardly, that is, away from the shaft 15. It is to be understood that each of the roller bearing blocks 32 35 is supported in the same manner, so that the two rollers 33, 33, are yieldingly pressed toward the bed 11 by the springs 37, 37. 38, 38^a indicate a printing plate in place in the bending machine, 38^a indicating a 40 sheet of metal forming the printing face, and 38 the somewhat thicker, softer backing made of electrotype backing metal.

45 In the operation of the device, a printing plate is placed in the machine with its upper edge against the stop bar 24^a and its lower edge against the presser bar 23. The operating handle 21 is then moved manually to swing the presser bar 23 in a direction toward the stop bar 24^a, thus curving 50 the plate until it conforms to the curvature of the bed 11. At this point in the description of the operation it should be noted that although the plate is thus bent to the same curvature of the bed 11, it would not 55 retain such curvature upon release of the presser bar 23 but would spring back somewhat. That is, there is a certain amount of elasticity in the plate which will cause it to spring back to a certain extent if the presser bar 23 should be released before performing any other operation. In the use of the machine, however, the plate is bent by means of the presser bar 23 as above described and then held in this position while 60 the shaft 15 is caused to make one rotation. 65

The knife 27 having been previously adjusted to the correct position, the shaft 15 is caused to rotate whereupon the knife 27 shaves from the upper surface of the backing 70 a thin piece of the electrotype backing metal as indicated by 38^b in Fig. 4. The rollers 33, 33, are adjusted so that the springs 37 will press them down tightly against the plate during the shaving operation, it being noted that one of the rollers 75 is just in advance of the knife and the other just behind it. These rollers serve to hold and press the plate tightly against the bed 11 just in front and just back of the cutting zone. The shaving taken off of the back of 80 the plate by the knife 27 is quite thin and comes off substantially in one large, flat sheet if the knife is properly adjusted and sharp enough.

85 After the plate has been shaved as above described, the presser bar 23, which may be manually held in position during the shaving operation, is released, and the plate removed.

90 As stated above, the printing plate has a certain amount of elasticity or resiliency so that being bent cold, and then released, it will spring back to a certain extent toward its original shape. I have found, however, that if the plate is bent cold and then 95 shaved on the back side as above described, it will not spring back as far as if the shaving operation has not been performed. In the practice of my invention, too much bending must not be given cold by means 100 of the presser bar 23. That is, if the plate in this step of the operation is bent or curved too much, there will be a certain amount of objectionable stretching or deformation of the face, that is, the amount 105 of curvature that can be given one plate by the practice of my invention in using one machine, is limited. The exact amount of curvature that can be given by one machine and without objectionable stretching or deformation of the face of the plate can be 110 determined by experimentation. It will be seen, however, that any desired curvature may be given to a plate by the use of two or more machines, in which case, the plate 115 is put through said machines successively. For example, I have found that one machine may be made to bend a plate from flat to what is known as number 70 curvature. Another may curve it from number 70 to 55; 120 another from 55 to 45, and so on.

125 In the construction of a bending machine in accordance with my invention it is to be noted that the bed 11 must have a curvature somewhat greater (that is, with a shorter radius) than the ultimate curvature desired to be given to the plate in the use of such machine. This is due to the fact that the plate, even after the shaving operation, will spring back to a certain extent toward its 130

original curvature. For example, if a machine is made to bend a plate from a number 55 curvature to a number 45 curvature, the curvature of the bed 11 must be somewhat greater (that is, for a shorter radius) than a number 45 curvature. In the use of such machine, the plate is first bent to a 55 curvature by other similar machines. It is then placed in the machine in question and by means of the presser bar 23 caused to conform to the curvature of the bed 11 which is, as stated, somewhat greater than a 45 curvature. The shaving operation is then performed, and upon release of the plate from the machine, it will spring back until it has a 45 curvature.

In general, it may be stated that in carrying out my invention, the plate must not be bent too much by one machine. If the plate is not bent by the presser bar 23 in any one machine, beyond the limit of its elasticity, all stretching and distortion will be substantially eliminated. In such case, the original bend given by the presser bar 23 not curving the plate beyond its limit of elasticity, will cause no distortion or stretching. The shaving operation carried on while the plate is held in this curvature will prevent it from going back to its original shape. It will be seen, therefore, that the machine will thus give the plate a certain amount of permanent curvature with no distortion or stretching. Obviously the curvature may be increased by successive operations in different machines to any desired extent. In practice, I have found, however, that in any one machine the first bend or curvature given by the presser bar 23 may be somewhat beyond the limit of elasticity of the plate without causing any objectionable distortion or stretching. The exact amount of curvature given to the plate by any one machine may be as great as desired as long as there is no objectionable stretching or distortion.

While I have illustrated and described a particular construction embodying my invention, I do not wish to be understood as intending to limit it thereto, as the same may be variously modified and altered without departing from the spirit and scope of the invention.

What I claim as new, and desire to secure by Letters Patent, is:

55 1. The method of curving printing plates which consists in bending the plate somewhat beyond the desired ultimate curvature

and shaving a portion off of the back thereof.

2. The method of curving printing plates which consists in bending the plate somewhat beyond the desired ultimate curvature and shaving a thin film off of the back thereof.

60 3. The method of curving printing plates which consists in forcing the plate face down on a bed having a curvature somewhat greater than the desired ultimate curvature and shaving a portion off of the back thereof while holding said plate in contact with said bed.

65 4. The method of curving printing plates which consists in forcing the plate face down on a bed having a curvature somewhat greater than the desired ultimate curvature and shaving a thin film off of the back thereof.

70 5. The method of curving printing plates which consists in forcing the plate face down on to a bed having a curvature somewhat greater than the desired ultimate curvature and shaving a portion off of the back thereof while maintaining pressure upon said plate in advance of the shaving zone to hold said plate in contact with said bed.

75 6. The method of curving printing plates which consists in forcing the plate face down on to a bed having a curvature somewhat greater than the desired ultimate curvature and shaving a portion off of the back thereof while maintaining pressure upon said plate in advance of and back of the shaving zone to hold said plate in contact with said bed.

80 7. The method of curving printing plates which consists in forcing the plate face down on to a bed having a curvature somewhat greater than the desired ultimate curvature and shaving a thin film off of the back thereof while maintaining pressure upon said plate in advance of the shaving zone to hold said plate in contact with said bed.

85 8. The method of curving printing plates which consists in forcing the plate face down on to a bed having a curvature somewhat greater than the desired ultimate curvature and shaving a thin film off of the back thereof while maintaining pressure upon said plate in advance of and back of the shaving zone to hold said plate in contact with said bed.

90 Witness my hand and seal this 8th day of September, 1925.

HARRY G. HOFF. [J.S.]
